UNITED STATES PATENT OFFICE.

CHARLES HENRY ERCANBRACK, OF ALDEN, ILLINOIS.

DEVICE FOR CONVERTING MOTION.

SPECIFICATION forming part of Letters Patent No. 286,596, dated October 16, 1883.

Application filed August 28, 1883. (No model.)

To all whom it may concern:

Be it known that I, CHARLES H. ERCANBRACK, a citizen of the United States, residing at Alden, in the county of McHenry and State of Illinois, have invented a new and useful Device for Converting Motion, of which the following is a specification, reference being had to the accompanying drawings.

This invention relates to devices for converting motion, and it has for its object to change the reciprocating movement of a windmill-pump shaft into a continuous rotary motion.

To this end it consists of a shaft journaled in the windmill-tower and carrying gear-wheels arranged to move in opposite directions, said gear-wheels engaging with a rack which is attached to the end of the pump-shaft of any ordinary windmill. These devices connect with suitable machinery for shelling corn, churning, &c., and thus, when the rack is reciprocated by the movement of the pump-shaft, this movement will be transmitted to the gear-wheels, which will convert it into a continuous rotary motion.

My invention consists in the above-described construction, and in certain other details, as hereinafter fully set forth, and particularly pointed out in the claims.

In the drawings hereto annexed, Figure 1 is a view of a windmill-tower, showing the arrangement of my improved devices. Fig. 2 is a perspective view of my improved devices detached. Fig. 3 is a vertical longitudinal section on line $y-y$, Fig. 5. Fig. 4 is a similar view taken at right angles to Fig. 3. Fig. 5 is a horizontal section on the line $z-z$, Fig. 3. Fig. 6 is a transverse section on the line, $x-x$, Fig. 4.

Like letters refer to corresponding parts in the several figures.

Referring to the drawings, A designates the windmill-tower, of any of the well-known forms of windmills, and B the pumping-shaft thereof, operated in the usual manner.

Journaled in the tower is a shaft, C, which is held from working out through its journals by means of collars c, having set-screws c', said shaft carrying two sets of devices acting independently of one another, said devices operating to convert a reciprocating movement into a rotary motion.

D D' designate gear-wheels working loosely around the shaft C, and provided with circular plates E E', secured to the back of the gear-wheels, said plates having square-shaped blocks F F' formed therewith. Suitably-shaped recesses f f' are cut from the blocks, and in these recesses are fitted pawls G G', having round heads g g', which fit and work within the recesses f f'. Circular caps H H' cover the blocks and pawls above mentioned and fit over the edge of the circular plates E E', the caps working around the shaft B and held from turning independently by means of set-screws h h', the latter working through an extension of the caps. The inner portion of the caps is hollowed out, and around the inner surfaces of the rims i i' is formed a continuous circumferential series of ratchet-teeth, j j', the blocks F F', with the pawls, fitting within the hollowed-out portion of the caps, the pawls engaging with the ratchet-teeth.

It will be seen that the heads g g' of the pawls fit within the recesses f f', which are shaped to retain the heads and yet allow free movement of the same, the front ends of the pawls projecting a short distance beyond the blocks F F', so as to readily engage with the ratchet-teeth in the caps. Two pawls are used for each of the gear-wheels D D', and engage with the ratchet-teeth in the caps, the extended corner l of the blocks limiting the play of the pawls. The recesses in the blocks, the arrangement of the pawls, and the ratchet-teeth in the caps are arranged in different positions for each of the gear-wheels D D'. Thus, as shown in the drawings, the position of the pawls G, the manner of fitting the same in the blocks, and the arrangement of ratchet-teeth j j' are all reversed in the gear-wheel D', so that when the gear-wheel D is operated it will revolve independently on the shaft, since the pawls G will slip readily over the ratchet-teeth j, while when the wheel D' is operated the pawls G' will be engaged with the teeth j', and said wheel D' cannot slip or revolve loosely around the shaft.

I designates a loose wheel fitted on shaft A, between the gear-wheels D D', said loose wheel running on a continuous track, J, formed inside the elliptical-shaped rack or frame K, around the middle portion. A series of teeth, L, is formed on opposite sides of the rack, out-

side the track J, the gear-wheels D D' meshing with said teeth when the rack is reciprocated, while the loose wheel I serves to hold the wheels in mesh only at a certain depth. 5 The rack or frame is formed at its upper and lower ends with extensions M, to the upper one of which is attached the pumping-shaft of any ordinary windmill, so that when the shaft is reciprocated a similar movement will be transmitted to the rack. As the rack descends the gear-wheels D D' are revolved and engage with the teeth L, the loose wheel I guiding the gear-wheels in their movements. By the revolution of the gear-wheels, the blocks, with 10 their pawls, are carried around inside the caps, the pawls G of wheel D being disengaged from the ratchet-teeth j of the cap H, so that said gear-wheel will revolve independently of shaft A without turning its cap, while, the pawls G' of the wheel D' being engaged with the ratchet-teeth j', the cap H' will be revolved, thereby turning the shaft A'. When the rack ascends, the wheels D D' are operated in a reverse direction, the pawls G of wheel D being engaged with the teeth j inside the cap H, so that said cap will be revolved, causing the continual revolution of the shaft A, while the pawls G' of the other wheel, D', will be disengaged, and thus the cap H' will not be operated. 15 This reciprocating movement is kept up, and will be converted into a continuous rotary motion, which will be imparted to the shaft A, the latter having at one end a pulley, N, connecting by a belt, O, with the operating-shaft of a corn-shelling machine, churn, washing-machine, or any other suitable means.

The operation and advantages of my invention are obvious. The construction is simple and durable, and works with admirable efficiency in converting a reciprocating movement into a rotary motion.

It will be obvious that various modifications may be resorted to without departing from the spirit or scope of my invention.

Having described my invention, I claim as new—

1. In a device for converting motion, a shaft journaled in the windmill-tower, and carrying two gear-wheels separated by a loose wheel, I, in combination with a rack or frame connected with the windmill-pump shaft at the upper end, said rack being provided with teeth on opposite sides, and a continuous track separating the teeth, the wheel I running on said track, for the purpose set forth.

2. In a device for converting motion, a shaft journaled in the windmill-tower and carrying two gear-wheels, between which works a loose wheel, I, and caps fitted over the outer ends 60 of the gear-wheels and connecting with the same, in combination with a rack or frame connecting with the operating-shaft at the upper end, and provided with teeth on the in-

side, and a continuous track between the teeth, said rack rotating the gear-wheels in opposite directions, while the wheel I runs freely on the track, and means, substantially as described, for permitting the free rotation of one of the gear-wheels, while the other wheel turns its cap, and thereby imparts motion to the 70 shaft, as set forth.

3. In a device for converting motion, the shaft C, connecting with the machinery to be operated, and journaled in the windmill-tower, gear-wheels revolving loosely on the shaft, 75 and provided with pawls on their outer faces, the pawls of one gear-wheel being engaged with its cap, while the pawls of the other wheel are disengaged with its cap, in combination with a rack or frame connecting with the 80 operating-shaft at the upper end, and provided with teeth on the inside, with which the gear-wheels mesh, as set forth.

4. The combination, with the gear-wheels, of circular plates having blocks secured to the 85 back of the wheels, recesses cut from the blocks, pawls G G', fitted within the recesses, and circular caps fitting over the outer ends of the gear-wheels, arranged as shown, for the purpose set forth.

5. The combination, with the gear-wheels, of circular plates having blocks formed therewith and secured to the back of the gear-wheels, recesses cut from the blocks, pawls G G', having round heads g g', which fit within 95 the recesses, and circular caps covering the whole and fitting over the outer ends of the gear-wheels, said caps being hollowed out in the inside and formed with a circumferential series of teeth with which the pawls alternately engage and disengage, for the purpose set forth.

6. The combination, with the rack or frame connecting with the operating-shaft at the upper end, said rack being formed with a track, K, around the inside middle portion, and a series of teeth outside the track on opposite sides, of a shaft journaled in the windmill-tower, and connecting with the machinery to be driven, gear-wheels loosely mounted on said 110 shaft, blocks formed on the back face of the wheels, recesses cut from the blocks, pawls having round heads fitting within the recesses, circular caps fitting over the outer ends of the gear-wheels, and provided with ratchet-teeth, 115 with which the pawls alternately engage and disengage, and wheels I, running between the gear-wheels on the track K, as and for the purpose set forth.

In testimony that I claim the foregoing as my 120 own I have hereto affixed my signature in presence of two witnesses.

CHARLES HENRY ERCANBRACK.
